FOLDABLE BAG-SUPPORTING STAND

Robert C. Gay, Bexley, and Charles F. Milan, Columbus, Ohio, assignors to Ohio Wire Products Co., Inc., Columbus, Ohio, a corporation of Ohio

Filed Oct. 7, 1968, Ser. No. 13,874

Term of patent 14 years

Int. Cl. D6—01

U.S. Cl. D49—34

FIG. 1 is a perspective view of a foldable bag-supporting stand in its erected condition, and showing our new design;

FIG. 2 is a side elevational view thereof; and

FIG. 3 is a perspective view showing the foldable bag-supporting stand in its folded condition.

The side of the foldable bag-supporting stand opposite that shown in FIG. 2 is a mirror image of FIG. 2.

We claim:

The ornamental design for a foldable bag-supporting stand, substantially as shown and described.
